US0D1070804S

(12) **United States Design Patent** (10) Patent No.: **US D1,070,804 S**
(45) Date of Patent: ** Apr. 15, 2025

(54) **WHITE NOISE SOUND MACHINE**

- (71) Applicant: **Perch Acquisition Co. 36, LLC**,
Boston, MA (US)
- (72) Inventor: **Brian P. Johnson**, Dallas, TX (US)
- (73) Assignee: **Perch Acquisition Co. 36, LLC**,
Boston, MA (US)
- (**) Term: **15 Years**
- (21) Appl. No.: **29/909,753**
- (22) Filed: **Aug. 10, 2023**
